MAGNETIC TAPE HAND PUNCH

George A. Wilson, Portola Valley, Calif., assignor to
Ampex Corporation, Redwood City, Calif.

Filed Feb. 11, 1974, Ser. No. 441,115

Term of patent 3½ years

Int. Cl. D19—02

U.S. Cl. D19—72

FIG. 1

FIG. 2

FIG. 1 is a front, top and right side perspective view of a magnetic tape hand punch showing my new design, the left side being substantially a mirror image of the right side and the bottom being conventionally plain; and

FIG. 2 is a back view of the punch shown in FIG. 1.

I claim:

The ornamental design for a magnetic tape hand punch, substantially as shown and described.
